UNITED STATES PATENT OFFICE

145,891

DESIGN FOR A SAXOPHONE

Earl J. Gillespie, Elkhart, Ind., assignor to The Martin Band Instrument Company, Elkhart, Ind., a corporation of Indiana

Application February 23, 1945, Serial No. 118,103

Term of patent 14 years

(Cl. D56—1)

To all whom it may concern:

Be it known that I, Earl J. Gillespie, a citizen of the United States, residing at Elkhart, in the county of Elkhart and State of Indiana, have invented a new, original, and ornamental Design for a Saxophone, of which the following is a specification, reference being had to the accompanying drawings forming a part thereof.

In the drawings:

Figure 4 is a fragmentary perspective view of the saxophone of Figure 1, showing the tear drop thumb rest and octave key lever thereof on an enlarged scale.

The characteristic feature of the design resides in the thumb rest, octave key lever and Eb and C key guards as shown in full lines in the drawings.

I claim:

The ornamental design for a saxophone, as shown and described.

EARL J. GILLESPIE.
